HEATER FOR SUPPLYING HOT GASES

Tallent H. Ransome, Oakland, Calif.

Application July 16, 1951, Serial No. 237,009

2 Claims. (Cl. 158—7)

1

This invention relates to an air heater which is specially designed for use in the drying of cotton and other products or materials.

In the processing of cotton particularly in the ginning operation thereof, it is essential that the moisture content of the cotton is reduced to a predetermined point to insure efficient ginning. Gas burners using butane or natural gas are employed to heat air by mixing it with products of combustion. The mixture is delivered to a drier by a fan or blower, hence, it is important that the air and gas ratio in the burner remains constant as improper combustion would otherwise result and discoloration of the cotton would take place. The atmosphere in a ginning plant is full of dust and lint and as the gas burners employed are of the Venturi type, material trouble has been encountered, due to the fact, that dust and lint tends to coat the inner surfaces of the Venturi tubes to such an extent as to change the gas and air ratio with poor combustion as a result.

An object of the invention is accordingly to prevent dust and lint from entering the Venturi tube of the burner; another object is to prevent dust and lint from entering the combustion zone of the heater as burning lint might pass through the heater and create a serious fire hazard; a further object is to provide an air heater employing a countercurrent air flow to prevent over heating of metal surfaces surrounding the combustion zone and thereby eliminating the use of fire brick or similar insulating material.

The heater structure is shown by way of illustration in the accompanying drawing which is a plan view of the heater said view being partially broken away and being partially shown in section.

In the drawing A indicates an elongated shell cylindrical in cross section and constructed of steel or like metal. One end of the shell is closed by a burner supporting head indicated at 2 while the opposite end is closed by a flue supporting head 3. Extending through the head 3 is a flue 4, this flue is centrally disposed within the cylindrical shell and extends substantially the length thereof. The flue terminates at a point adjacent the burner supporting head 2, but is spaced therefrom as shown. The end of the flue adjacent the burner supporting head 3 is open as shown at 5 while the opposite end which extends through the flue supporting head is connected with the suction side or inlet of a blower 6.

A main burner 7 of the Venturi type is supported by the burner head 2 and extends there-

2

through, it is positioned in alignment with the flue 4 and the flame of the burner is accordingly directed into the open end thereof. Formed in the shell adjacent the flue supporting head are a plurality of openings which are covered by a screen 8, hence, when the burner and blower are in operation air will enter through the screened openings and will flow in the direction of arrows a toward and against the burner and its supporting head, the air is here deflected and mixes with the flame of the burner and then enters the open end of the flue and passes through it to the blower which delivers the mixed products of combustion and hot air to the drier.

15 The air flow through the heater is a countercurrent as it flows in the direction of arrows a when entering and in the direction of arrow b when discharging through the flue. This countercurrent is important as it cools the burner supporting head and the adjacent portion of the outer shell which surrounds the combustion zone to such an extent that fire brick or similar insulation may be entirely eliminated. This reduces cost and weight and furthermore promotes combustion and overall efficiency.

20 The Venturi type burner 7 is provided with an air inlet head 9 and this is connected with the interior of the shell A by means of a tube 10 which is provided with a valve 11 so that a correct air and gas ratio may be maintained in the burner. Inasmuch as all air entering the shell of the heater must pass through the screen 8 there will be no dust or lint to coat the inner surface of the Venturi tube, this precludes faulty burner performance, furthermore, there is no lint to enter the combustion zone and all fire hazard is accordingly eliminated.

25 The main burner 7 is usually provided with a pilot burner such as indicated at 12. This burner may be installed in the same manner as the main burner to prevent coating or clogging of its inner surfaces with lint or dust, or it may as here shown be installed within the shell where it is kept comparatively cool by the incoming air and where its air intake is open to the dust and lint free air within the shell.

30 The temperature of the air delivered to the cotton drier may be around five hundred degrees F. or more, but it may be delivered to the drier at any desired temperature by regulating the flame area of the main burner or by admitting additional cool air to flue 4 by means of a louver 14. The air entering at this point may or may not be screened as it is so far removed 35 from the combustion zone that if lint enters there

is no danger of it becoming ignited and creating a fire hazard.

The heater as a whole is simple in construction and efficient in operation. It does not require a heavy underpinning or foundation as it is comparatively light in weight due to elimination of fire brick or other insulation. Fire hazard is done away with due to the screening of all air and the main and pilot burners can be relied upon for continuous and efficient performance as no dust lint can accumulate on their interior surfaces, and while this and other features of the heater have been more or less specifically described and illustrated, it should be understood that changes may be resorted to within the scope of the appended claims, and that changes in materials and the parts employed may be such as experience or specific use may demand.

Having thus described my invention, what I desire to claim and secure by Letters Patent is:

1. In a heater of the character described an elongated cylindrical shell, a head at each end forming a closure therefor, a Venturi type gas burner having its discharge end extending through one head, a discharge flue extending through the other head said flue extending through the length of the shell and terminating in front of the discharge of the burner but being spaced therefrom and being open to receive the flame of the burner, a screen covered air inlet formed in the shell adjacent the other end of the flue, and a blower connected with the discharge flue to induce a flow of air lengthwise of the shell toward the burner supporting head and then in the reverse direction through the discharge flue, an air inlet head on the burner and

means for conveying air from the interior of the shell to the air inlet head of the burner.

2. In a heater of the character described a closed elongated shell, a discharge flue extending through one end of the shell and terminating at a point adjacent the opposite end but being spaced therefrom said terminating end being open, a Venturi type gas burner having its discharge end entering the shell and disposed in front of the open end of the flue to direct its flame into the flue said burner having its gas and air inlet exterior of the shell, a pilot burner disposed wholly within the shell at one side of the discharge end of the first named burner, means for maintaining a flow of air from the opposite end of the shell toward both burners to cool the same and also to cool the portion of the shell surrounding the flame area of the burners said air passing through the flame area and entering the open end of the flue and flowing in a reverse direction therethrough, means for conveying air from the interior of the shell to the air inlet of the first named burner, and means for filtering all of the air entering the shell.
